UNITED STATES PATENT OFFICE

2,689,349

STIFFENING AND STRETCHING DEVICE

William B. White, Bismarck, N. Dak.

Application May 21, 1951, Serial No. 227,349

2 Claims. (Cl. 2—132)

1

This invention relates to a device for stiffening or stretching fabrics as for example a shirt collar and has for its primary object to provide a device of extremely simple construction capable of being readily applied to spaced portions of a piece of fabric such as a shirt collar and which will urge the fabric portions engaged by the device away from one another to retain said portions in a stretched condition and which being substantially rigid will prevent folding or wrinkling of the collar or fabric between the portions thereof engaged by the device to thereby stiffen the fabric or collar.

More particularly, it is an object of the present invention to provide a stretching and stiffening device of extremely simple construction composed of a minimum of parts enabling the device to be manufactured in restricted sizes and to have a very restricted cross sectional size so that the device may be readily concealed beneath a collar wing or behind a piece of fabric without producing noticeable bulge therein.

Another object of the invention is to provide a stiffening and stretching device involving a novel combination of parts assembled in a novel manner to facilitate the operation of the device and to eliminate any tendency of the parts to bind when extended or retracted.

A further object of the invention is to provide a device of relatively sturdy construction the parts of which are so assembled that any tendency of the parts to buckle is substantially eliminated.

Various other objects and advantages of the invention will hereinafter become more fully apparent from the following description of the drawing, illustrating a presently preferred embodiment thereof, and wherein:

Figure 1 is a fragmentary front elevational view of the upper portion of a shirt having a soft collar and showing a pair of the stiffening and stretching devices in dotted lines applied to the innerside of the collar wings, to illustrate a preferred application of the invention;

Figure 2 is a plan view of one of the stiffening and stretching devices;

Figure 3 is an edge elevational view thereof looking from right to left of Figure 2, and

Figure 4 is a perspective view of the same.

Referring more specifically to the drawing, the stretching and stiffening device in its entirety is designated generally 5 and is composed of two corresponding slidably connected sections 6 and 7 and a contractile coiled spring 8.

Each of the sections 6 and 7 is formed from

5 a single strand of relatively stiff wire and each section 6 and 7 includes an elongated straight shank portion 9 having an eye 10 formed at one end of the shank 9 and which forms one terminal of the strand from which the section 6 or 7 is formed. The eye 10 of each section is disposed at substantially a right angle to the axis of its shank 9. Each shank 9, adjacent its eye 10 is looped to provide a second eye 11 which eyes 11 are disposed substantially longitudinally of the shanks 9.

10 An elongated loop, designated generally 12, is formed in each shank 9 near its opposite end and longitudinally thereof. Each loop 12 includes laterally spaced substantially parallel legs 13 and 14. The leg 13 has a curved inner end 15 merging with the straight portion of its shank 9, and the outer ends of the legs 13 and 14 are connected by an outer transverse loop portion 16 which is curved upwardly relatively to the plane of the legs 13 and 14, as best seen in Figures 3 and 4. The other terminal of each shank 9 is formed by a substantially straight strand portion 17 having an inner end connected to the inner end of the leg 14 by a curved strand portion 18 which is curved inwardly toward the leg 13 and inclined upwardly away from said leg 14 and relatively to the plane of the legs 13 and 14. The strand end 17 is inclined downwardly and outwardly from its inner end and extends outwardly between the legs 13 and 14 and beneath the outer upwardly curved loop portion 16. As best seen in Figure 3, the strand end 17 is spaced from the upper part of the loop portion 16 and extends a short distance therebeyond and terminates in a tapered piercing point 19.

15 The shanks 9 of the sections 6 and 7 are disposed in overlapping relationship and in engagement with one another and the eye 10 of each shank 9 slidably engages the other shank 9 for maintaining the shanks in substantially parallel relationship and for slidably connecting the shanks for movement longitudinally of the device 5 in either direction. The contractile spring 8 is coiled around the overlapping portions of the shanks 9 and the ends of the spring 8 are secured to the eyes 11, as seen at 20, so that the spring 8 tends to pull the eyes 11 toward one another and to thus displace the shank loops 12 away from one another or toward extended positions.

20 The spring 8 is of relatively small diameter being only sufficiently large to engage around the shank portions 9 without assuming a frictional

engagement therewith and said spring may be coiled around said shank portions 9 after the eyes 10 of each shank has been formed around the other shank or the shanks may be inserted through the spring 8 and the eyes 10 and 11 thereafter formed therein.

It will be noted that the eyes 11 are disposed substantially perpendicular to the plane of the loops 12 and are preferably inclined slightly so that each eye 11 overlies a portion of the shank 9 of the other section. Further, the spring 8 is coiled in such a direction that the convolutions thereof tend to urge the eyes 11 toward aligned positions so that each eye 11 bears against the shank of the other section and in this manner the loops 12 are maintained in substantially the same plane, as illustrated in Figure 3.

The loop portions 16 each perform a dual function in that said loop portions form fingernail rests one of which is adapted to be engaged by the nail of the index finger and the other by the nail of the thumb for displacing the loops 12 toward one another to retract the stretching and stiffening device 5 and to thereby stretch and tension the spring 8. With the device 5 thus retracted or shortened and while it is held as previously described, the device 5 is positioned against a piece of fabric to be stretched or stiffened as for example the inner side of a collar wing, as illustrated in Figure 1, with the points 19 extending downwardly and toward the fabric or collar wing 21. By then releasing the pressure on the loop portions 16, the spring 8 will draw the eyes 11 toward one another and in so doing will displace the loops 12 and points 19 away from one another so that the points 19 will pierce the fabric to thereby stretch and stiffen the fabric or collar wing portions disposed between said points. The loop portions 16 perform a secondary function in that said portions 16 constitute stops which engage the fabric to limit the extent of penetration of the spike portions 17. Obviously, the amount of tension applied to the fabric may be varied by varying the extent that the spike points 19 are displaced toward one another before being applied to the fabric.

It will be noted that the contractile spring 8 has no tendency to buckle when under tension but instead tends to maintain the sections 6 and 7 in substantially straight aligned relationship and it will likewise be apparent that the guide eyes 10 could be omitted without materially affecting the functioning of the device 5.

Various modifications and changes are contemplated and may obviously be resorted to, without departing from the spirit or scope of the invention as hereinafter defined by the appended claims.

I claim as my invention:

1. A fabric stretching and stiffening device comprising a pair of corresponding slidably connected sections and a contractile coiled spring, said sections each being formed of a strand of relatively stiff wire and each including an elongated shank portion, said shank portions extending slidably through the contractile coiled spring and having spring engaging eyes adjacent corresponding ends thereof formed in the overlapping portions of said shanks and between which said spring is disposed, the ends of said spring being anchored to said spring engaging

eyes for urging the eyes toward one another, the strands forming said sections having spike portions at their opposite, remote ends adapted to pierce spaced portions of a piece of fabric to provide a substantially rigid uninterrupted extensible member extending between the spike portions and spring urged to an extended position for stretching and stiffening the fabric between the spike portions, and the strand of each section having a loop adjacent the spike portion thereof and from which the spike point projects, each of said loops including substantially parallel coplanar legs disposed longitudinally of the device between which the spike of said section is disposed, said loop including an upwardly curved transversely extending outer portion disposed over a portion of the spike forming a fabric engaging stop and a fingernail rest and beyond which the pointed end of the spike projects, said spring engaging eyes being disposed at an angle to the plane of the legs of the loops and each being retained by the spring in engagement with the shank of the other section for maintaining said loops in coplanar relationship.

2. A fabric stretching and stiffening device comprising a pair of corresponding slidably connected sections and a contractile coiled spring, said sections each being formed of a strand of relatively stiff wire and each including an elongated shank portion, said shank portions extending slidably through the contractile coiled spring and having spring engaging eyes adjacent corresponding ends thereof formed in the overlapping portions of said shanks and between which said spring is disposed, the ends of said spring being anchored to said spring engaging eyes for urging the eyes toward one another, the strands forming said sections having spike portions at their opposite, remote ends adapted to pierce spaced portions of a piece of fabric to provide a substantially rigid uninterrupted extensible member extending between the spike portions and spring urged to an extended position for stretching and stiffening the fabric between the spike portions, and the strand of each section having a loop adjacent the spike portion thereof and from which the spike point projects, the terminals of said strands located adjacent the spring engaging eyes and remote from the spikes each being provided with a guide eye, said guide eyes being disposed at substantially right angles to the axes of said shanks and the guide eye of each section slidably engaging the shank of the other section, said guide eyes being disposed beyond the ends of the contractile spring and beyond said spring engaging eyes.
